His Attorney.

UNITED STATES PATENT OFFICE

2,311,825

POST STRAIGHTENER FOR PIPES, BARS,
AND THE LIKE MATERIALThomas H. Graham, Ellwood City, Pa., assignor
to National Tube Company, a corporation of
New Jersey

Application April 29, 1939, Serial No. 270,851

1 Claim. (Cl. 153—32)

The present invention relates to an apparatus for straightening pipes, bars and the like material, and more particularly to a straightener having V-shaped pipe engaging rollers.

An object of the present invention is to provide means for adjustably supporting one of the material engaging rollers with respect to the other material engaging roller.

A further object of the present invention is the provision of V-shaped pipe or bar engaging rollers which serve as gripping means for the pipe or bar while a kink or bend is being straightened over the lower V-shaped roller.

Other objects and advantages will become apparent as the description proceeds and reference is had to the accompanying drawing, in which:

Figure 1 is a side elevation of the present invention;

Figure 2 is an elevation of Figure 1 at right angles thereto;

Figure 3 is a view similar to Figure 1 of a straightener having a V-shaped block in combination with a roll;

Figure 4 is a side view of Figure 3; and

Figures 5 and 6 are similar views in which V-shaped blocks are used.

In the drawing, the numeral 2 represents an upper roll bracket which is attached for vertical adjustment to the rear of a post 3 by a bracket 4. This roll bracket is made up of spaced bent steel bars secured together by bolts 5. Positioned between the spaced steel bars of the upper roll 2 is a top adjustment rod 6, the lower end of which is threaded to be interconnected with the bottom adjustment rod 7 by means of a turnbuckle 8. The bottom adjustment rod 7 is threaded on each end so as to be connected to the turnbuckle on one end and adjustably connected on the other end to a lower bracket 9 by the nuts 10 and 11.

The upper bracket 4 is provided with an upwardly extending plate 12 positioned on one side thereof and provided with a slot 14 within which is adapted to slide the bolt 15, the latter cooperating to hold the spaced plates forming the upper roll bracket and the enlarged head portion of the top adjustment rod 6 together.

At the top of said post 3 is bolted, or otherwise secured, in any conventional manner, a stationary roll bracket 16 comprising spaced plates secured on each side of said post. Positioned between said adjustable and stationary roll brackets, in any conventional manner, are V-shaped rollers 17 so positioned and arranged with respect to each other that they have opposite points of contact

upon a pipe or bar 20 passing therebetween for straightening purposes.

In the straightener shown in Figures 3 and 4, the upper roll bracket 2 is of similar construction and is supported on the post 3 by a bracket 18. The rod 6 is threaded upon its end so that the upper roll bracket is adjustable in order for the roller 17 to contact the pipe or bar 20 on one wall of said pipe or bar, while a V-shaped block 21 contacts the other wall of said pipe or bar, the block 21 being positioned by an adjustable bracket 22 having a slot 23 through which a bolt 24 passes to fix the bracket to the post 3. In Figures 5 and 6, there are shown two V-shaped blocks 21 and 21^a, the block 21 being mounted by an arrangement much the same as shown by Figure 3 and, therefore, the same numerals being used to identify the equivalent parts. In this showing, the V-shaped blocks are used to hold the tube or bar while the operator pulls down on the outer end to straighten out the kinks and bent sections. The tube 20 must be released from the frictional grip of the blocks to move from point to point in accordance with the operator's judgment.

However, under the V-shaped roller construction, all that is necessary is for the operator to pull the tube or bar through the rollers in a longitudinal direction as he pulls down on it and at no time is he required to release the frictional grip of the rollers upon the pipe.

It is to be noted that in all the examples disclosed, the bending of the work necessary to straighten it places the post 3 in compression and the rod 6 in tension, the reaction location being in all instances at the point where the rod connects with the bracket which is positioned at the lower portion of the post. In devices of this character torque is created when they are placed in operation and in prior art structures the location of this torque must occur at the top of the post where it is most apt to flex, whereby to necessitate an extremely heavy post if a stable structure is to be attained. In the present invention the torque being at the lower portion of the post, a lighter post may be used without loss of stability, the post having greater stiffness at its lower portion.

While I have shown and described specific embodiments of the present invention, it will be seen that I do not wish to be limited exactly thereto, since various modifications may be made without departing from the scope of the invention, as defined by the following claim.

I claim:
In apparatus for straightening a pipe, bar or

similar workpiece, the combination with a post having an upper end and a lower end positioned in the ground to hold the post, an upper bracket arm extending laterally from the post at substantially right angles thereto, and a similar lower bracket arm, an adjustment rod mounted in these brackets, means permitting adjustment of the adjustment rod, the said brackets holding the adjustment rod spaced away from the post and substantially parallel thereto longitudinally, the adjustment rod having an upper end and a lower end, a bracket on the upper end of the rod, a V-shaped roller in the bracket adapted to engage and retain the pipe, a second bracket mounted on the post and projecting substantially straight out beyond the upper end of the post, a V-shaped

5 roller in the bracket similar to the above-mentioned V-shaped roller, the rollers being adapted to grip a pipe or bar at spaced opposite locations while permitting sufficient length of the pipe or bar to extend beyond the rollers sufficiently to enable the pipe or bar to be grasped manually and straightened manually while being held between the said rollers, straightening of the work placing the post in compression and the adjustment rod in tension, the bracket arms on the post being positioned so that resulting reaction between tension and compression is transmitted to the lower bracket arm and lower portion of the post for assuring maximum rigidity of the post.
